Filed Nov. 2, 1959, Ser. No. 58,190

Term of patent 14 years

(Cl. D52—7)

Fig. 1 is a perspective view of a thermostat, showing our new design.

Fig. 2 is a front elevational view thereof.

The undisclosed side of the thermostat is substantially the same in appearance as the side shown. The perforations seen on the face of the thermostat are continued throughout the area.

We claim:

The ornamental design for a thermostat, as shown and described.
